UNITED STATES PATENT OFFICE.

ROBERT M. DOWNE, OF BEAVER FALLS, PENNSYLVANIA, ASSIGNOR TO KEYSTONE DRILLER CO., OF BEAVER FALLS, PENNSYLVANIA, A CORPORATION OF PENNSYLVANIA.

COMPRESSED-AIR WATER-ELEVATOR.

No. 906,395.

Specification of Letters Patent.

Patented Dec. 8, 1908.

Application filed March 30, 1907. Serial No. 365,506.

To all whom it may concern:

Be it known that I, ROBERT M. DOWNE, a citizen of the United States, residing at Beaver Falls, in the county of Beaver and State of Pennsylvania, have invented a new and useful Compressed-Air Water-Elevator, of which the following is a specification.

This invention relates more particularly to means for elevating water or other liquid by 10 means of fluid under pressure, as for instance, compressed air.

The primary object of the present invention is to provide novel, simple and effective means of the above character, said means insuring the delivery of a proper proportion of air or motive fluid with the column of water or liquid, and moreover being substantially automatic in its nature, so that as long as motive fluid is turned into the elevating means 20 and there is a supply of liquid, the latter will be elevated.

The preferred embodiment of the invention is illustrated in the accompanying drawings, wherein:

25 Figure 1 is a vertical sectional view through a well, showing the elevating means therein, portions of said elevating means being shown in section. Fig. 2 is a vertical sectional view through the elevating means. Fig. 3 is a cross sectional view on the line 3—3 of Fig. 1. Fig. 4 is a cross sectional view on the line 4—4 of Fig. 1. Fig. 5 is a cross sectional view on the line 5—5 of Fig. 1. Fig. 6 is a detail sectional view on an enlarged scale of the upper 30 head of the pump barrel. Fig. 7 is a plan view of the same. Fig. 8 is a top plan view of the lower head of the pump barrel.

Similar reference numerals designate corresponding parts in all the figures of the 40 drawings.

The structure herein disclosed is shown in a well 9 having a suitable curb 10, which is covered with a cap 11. The particular character of the well, is however, not important.

45 The mechanism consists of a barrel that comprises a cylinder 12, into the upper and lower ends of which are threaded heads 13 and 14. The lower head 14 has a central inlet opening 15 controlled by an inwardly opening 50 valve 16 having a stem 17 slideable in a web 18 that extends across the inlet opening, as shown in Fig. 8. The upper head 13 is provided with two openings 19 and 20, which

may be of different diameters. A liquid conducting pipe 21 has sections threaded into the opening 19, the lower section 21^a extending downwardly into the lower portion of the pump barrel, and being of considerably less diameter than the same. The said liquid conducting pipe extends through the 55 cap 11, and is connected by a coupling 22 to a delivery pipe 23 extending to any desired point. A motive fluid supply pipe 24 leading from any suitable source of supply, as for instance, an air compressor, extends downwardly through the cap 11 into the well 9 alongside the conducting pipe 21. This motive fluid supply pipe also has sections, which are threaded into the opening 20 of the upper cap, and the lower section 24^a extends downwardly within the barrel alongside the section 21^a of the conducting pipe. It will thus be evident, particularly by reference to Fig. 2 that the lower discharge end of the motive fluid supply pipe communicates with the 60 lower portion of the chamber or barrel, and in like manner, the lower inlet end of the liquid conducting pipe communicates with the lower portion of the chamber or barrel directly contiguous to the discharge end of the 65 motive fluid supply pipe. These ends are connected by a coupling 25, the lower end of the section 21^a of the conducting pipe being threaded into said coupling, the lower end 70 24^a of the motive fluid supply pipe section 75 being loosely engaged in an opening in said coupling. The lower portion of this coupling is cupped, as shown at 26, forming a channel with an open bottom, and it will be evident by reference to Fig. 2 that both pipes 80 communicate with this channel. The coupling is of less cross sectional area than the 85 barrel cylinder 12.

In the upper portion of the section 21^a of the liquid conducting pipe is a vent 27 constituting means of communication between 95 the interior of the pipe and the upper portion of the pump barrel or chamber. Direct communication is also established between the motive fluid supply pipe and the liquid conducting pipe at the upper end of the pump barrel. For this purpose, a by-pass conduit 28 is threaded into an opening 29 formed between the openings 19 and 20 in the upper head, and this conduit, which has one end 100 105 thus in communication with the motive fluid

supply pipe, has an upwardly extending discharge end 30, disposed within the liquid conducting pipe.

The operation of the structure is substantially as follows:—The pump barrel or chamber is placed below the level of the water in the well. Assuming therefore that the barrel is full or substantially full of water, if air under pressure or other motive fluid is admitted to the pipe 24, the same will flow downwardly into the barrel. A portion of this air or fluid will be directed by the lower channel 26 of the coupling 25 into the inlet end of the conducting pipe, while another portion underflowing the coupling 25 rises through the water in the barrel to the top of said barrel. This latter air will gradually displace the water in the barrel, forcing the level lower and lower, and as the only exit is through the liquid conducting pipe, a column of water aerated by the air directed into the pipe by the channel 26 will be elevated through the pipe 21 to the point of discharge. This current of water passing into the pipe will tend to carry more and more of the air in with it, and the cupped end of the coupling will tend to harbor the air at the opening so that a proper proportion of the air will be carried upwardly with the water. The air thus rising in the liquid conducting pipe will expand more and more, as it rises to points where the pressure is lower. In time, the accumulation of air under pressure in the barrel will overcome the hydrostatic pressure in the liquid conducting pipe, and consequently the barrel or chamber will be emptied through the same. Simultaneously with this emptying action, the air pressure which has been accumulating, will be reduced to substantially atmospheric pressure, inasmuch as the air can exhaust freely through the larger liquid conducting pipe. At this instant of time, the pressure of the water in the well will lift the lower valve and rush into the cylinder, filling it almost instantaneously nearly to the top; inasmuch as the vent 27 will allow the escape of the air. A portion of the inrushing water will at the same time rise in the section 21^a of the liquid conducting pipe, and as soon as the vent 27 is closed, the lower valve will also close because of the increasing pressure of air in the barrel. The above described action will then be again repeated. The use of the by-pass is important, inasmuch as it assists in relieving the air pressure from the barrel while the latter is filling, and as soon as the water rises to cover the vent, an upward suction takes place due to the upturned air jet of the by-pass so that the cylinder is soon emptied of water.

From the foregoing, it is thought that the construction, operation, and many advantages of the herein described invention will be apparent to those skilled in the art, without further description, and it will be under-

stood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

1. In mechanism of the character set forth, the combination with a pump chamber having an inlet, of a conducting pipe having its inlet end communicating with the chamber, a motive fluid supply pipe having its discharge end communicating with the chamber, and means located within the chamber for directing a portion of the motive fluid from the discharge end of the supply pipe to the inlet end of the conducting pipe, said means permitting the escape of a portion of the motive fluid into the chamber.

2. In mechanism of the character set forth, the combination with a pump chamber having a liquid inlet, of a liquid conducting pipe having its inlet end communicating with the chamber, a motive fluid supply pipe having its discharge end communicating with the chamber, said pipes having their lower ends located within the lower portion of the chamber, and means located within the chamber and connecting the lower ends of the pipes for directing a portion of the motive fluid from the discharge end of the motive fluid supply pipe to the inlet end of the conducting pipe, said means permitting the escape of a portion of the motive fluid into the chamber.

3. In mechanism of the character set forth, the combination with a pump barrel, of a liquid conducting pipe communicating with the lower portion thereof, a motive fluid supply pipe, and a connection between the pipes that constitutes means for admitting a portion of the motive fluid into the barrel to force the liquid therefrom into the liquid conducting pipe and also constituting means for simultaneously admitting a portion of the motive fluid into the conducting pipe for elevating the liquid therein.

4. In mechanism of the character set forth, the combination with a pump barrel having a valved liquid inlet in its lower end, of a motive fluid conducting pipe extending downwardly into the barrel and having its lower inlet end disposed in the lower portion of said barrel, a motive fluid supply pipe extending downwardly into the barrel and having its lower discharge end communicating with the lower portion of the barrel contiguous to the inlet end of the conducting pipe, and a coupling secured to the lower ends of said pipes and having a cupped under side forming a channel for directing a portion of the motive fluid from the motive fluid supply pipe to the conducting pipe.

5. In mechanism of the character set forth, the combination with a pump barrel com-

- prising a cylinder and heads fixed to the ends thereof, the lower head having an inlet, the upper head being provided with a plurality of openings, of a valve controlling the inlet, 5 a motive fluid conducting pipe extending through one of the openings in the upper head downwardly into the lower portion of the barrel, a motive fluid supply pipe extending downwardly through the other opening 10 in the upper head and having its discharge end located in the lower portion of the barrel, and a coupling connecting the lower ends of the pipes and having a cupped under side forming a channel with which the lower ends 15 of the pipes communicate, said channel having an open lower side.
6. In mechanism of the character set forth, the combination with a pump barrel, of a liquid conducting pipe extending into and 20 communicating with the lower portion thereof, a motive fluid supply pipe extending into the barrel, and a connection between the pipes located in the pump barrel, and constituting common means for admitting a portion 25 of the motive fluid from the supply pipe into the barrel to force the liquid therefrom into the conducting pipe and simultaneously admitting a portion of said motive fluid into the conducting pipe to elevate the liquid 30 therein.
7. In mechanism of the character set forth, the combination with a pump chamber, of a liquid conducting pipe extending downwardly within the chamber to the lower portion 35 thereof, said pipe having a vent in its upper portion that communicates with the upper portion of the chamber, a motive fluid supply pipe extending downwardly within the chamber and having its lower end disposed 40 contiguous to the lower end of the conducting pipe, and a coupling connecting the lower ends of the pipes within the chamber and
- having a channel in its under side that constitutes means for directing motive fluid from one pipe to the other. 45
8. In mechanism of the character set forth, the combination with a pump barrel comprising a cylinder and heads threaded into the ends thereof, the lower head having an inlet, of an inwardly opening valve controlling the inlet, a liquid conducting pipe extending downwardly through the upper head into the lower portion of the barrel and having a vent communicating with the upper portion of said barrel, a motive fluid supply pipe extending downwardly into the lower portion of the barrel, a coupling connecting the lower ends of the pipes and having a cupped under side forming a channel with which the lower ends of said pipes communicate, and a by-pass conduit located in the upper head and extending from the motive fluid supply pipe into the liquid conducting pipe, said by-pass conduit having an upwardly extending discharge nozzle within the 55 liquid conducting pipe. 60
9. In mechanism of the character set forth, the combination with a pump barrel including a cylinder and an upper head having spaced openings, said upper head also having 70 communication between the openings, a liquid conducting pipe engaged in one opening, and a motive fluid supply pipe engaged in the other opening, said communication permitting motive fluid to pass from the 75 supply pipe to the conducting pipe.

In testimony, that I claim the foregoing as my own, I have hereto affixed my signature in the presence of two witnesses.

ROBERT M. DOWNE.
